Des. 200,130
Patented Jan. 19, 1965

200,130

XEROGRAPHIC CAMERA

Robert G. Plantholt, 1184 W. Tienken Road,
Rochester, Mich.

Filed Jan. 2, 1964, Ser. No. 78,008

Term of patent 14 years

(Cl. D61—1)

FIG. 1

Des. 200,130

PAGE 2

FIG. 2

FIG. 5

FIG. 1 is a front perspective view of a xerographic camera; FIG. 2 is a front elevational view thereof; FIG. 3 is a left side elevational view thereof; FIG. 4 is a rear elevational view thereof; and FIG. 5 is a top view thereof.

I claim:

The ornamental design for a xerographic camera, as shown.
